(57) **CLAIM**

The ornamental design for a lid device for analyzer container, as shown and described.

DESCRIPTION

FIG. 1 is a perspective view of a lid device for analyzer container of the present invention;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is the same perspective view of the lid device for analyzer container shown in FIG. 1 with environmental structure included;

FIG. 9 is the same perspective view of the lid device for analyzer container shown in FIG. 1 shown in a condition of use with the environmental structure seen in FIG. 8; and, FIG. 10 is a cross-sectional view taken along line 10-10 of FIG. 2 of the lid device for analyzer container shown in a condition of use with the environmental structure.

The broken lines are included for the purpose of illustrating environmental context for the container for analyzer that

(Continued)

forms no party of the claimed design. Additionally, the unevenly broken lines in the drawings define the limits of the claimed design.

1 Claim, 5 Drawing Sheets
